SHAVING BRUSH AND DEVICE FOR FORMING THE SAME

Filed Sept. 4, 1929

INVENTOR.
HARRY A. JAVINS.

BY *Henry N. Young*
ATTORNEY

UNITED STATES PATENT OFFICE

HARRY A. JAVINS, OF ELK GROVE, CALIFORNIA, ASSIGNOR TO ANDREW ELLIOTT AND
GUY G. FOULKS, OF ELK GROVE, CALIFORNIA

SHAVING BRUSH AND DEVICE FOR FORMING THE SAME

Application filed September 4, 1929. Serial No. 390,296.

The invention relates to an improved shaving brush and to a method and apparatus for producing the same.

An object of the invention is to provide a particularly inexpensive shaving brush for discard after a single use thereof.

Another object of the invention is to provide an improved and unitary brush of the class described which includes a handle portion.

A further object of the invention is to provide an improved and simplified process for manufacturing the brush.

Yet another object is to provide apparatus for carrying out the process of the invention in a single operation.

The invention possesses other objects and features of advantage, some of which, with the foregoing, will be set forth or be apparent in the following description of a preferred embodiment thereof and in the accompanying drawings, in which,

Figure 1 is a front elevation of apparatus for producing the brush, the brush elements being mounted therein and the working parts of the apparatus being inoperatively disposed.

Figure 2 is a side elevation of the apparatus and brush elements, portions of certain elements being broken away to show the same in section.

Figure 3 is a fragmentary view of the showing of Figure 2, but disclosing the brush forming elements thereof operatively engaging the elements of a completed brush.

Figure 4 is a sectional view at 4-4 in Figure 2 but with the brush forming elements as in Figure 3.

Figure 5 is a side view of a bunch of fibres for forming a brush.

Figure 6 is a view of a pre-formed ferrule for incorporation in the brush.

Figures 7 and 8 are elevations of a completed brush, the views being taken at right angles to each other.

Figure 9 is an elevation of a brush charged with soap and wrapped for vending, a portion of the wrapper being broken away.

Referring particularly to Figures 5 to 9 inclusive, the brush 11 of my invention is

seen to be formed of a cylindrical bunch 12 of suitable bristles doubled intermediately to form a fold 13 which provides a handle for the brush and to bring the bristle ends into lateral juxtaposition to provide the brush tuft portion 14. For securing the bristles in brush forming relation, a banding ring or a ferrule 15 is fixed about the doubled bristle bunch at the juncture of the handle and tuft portions of the brush. The complete brush is then seen to be made up solely of the bristle bunch 12 and ferrule 15.

In providing the present brush, it is a particular purpose to minimize costs whereby a brush may profitably be discarded after a single use thereof. For this purpose, the bristles used preferably comprise suitable vegetable fibres, such being very much less expensive than are animal bristles; of the available fibres, those of sisal have been found particularly satisfactory for the purpose, both as to qualities of the tuft provided and the cost thereof. For the aforesaid reason, the ferrule 15 is also of inexpensive material and structure and preferably comprises a closed and non-stretching ring of wire or cord; in the present instance, the ferrule 15 is formed of a length of stiff wire shaped to provide a torus of a single strand of the wire, with the wire ends contacting but not necessarily fixed together.

The labor and apparatus involved in applying the ferrule to the bristle bunch to provide the brush must also, of course, be a minimum, and the preferred method of the present invention is to provide the ferrule as a pre-formed element and engage the bunch of bristles therein to form the brush by a single operation. The latter operation is effected by forcing the intermediate portion of the bristle bunch transversely against and axially through the ferrule to provide the handle loop and tuft portions of the brush, the ferrule compressedly fitting the doubled bristle bunch whereby a permanent structure results.

A preferred apparatus for carrying out the aforesaid process is disclosed in Figures 1 to 4 wherein the working parts of the device are carried on an upright standard or pedestal 16, mounted on a base 17. As particu-

larly shown, upper and lower brackets 18 and 19 respectively are adjustably mounted on the standard at intermediate points thereof. The upper bracket 18 carries a plunger 21 for vertical reciprocation therein and said plunger 5 is provided at the lower end thereof with a plate element 22 provided with a forked portion 23 at its lower and free end. Preferably, and as shown, the element 22 forms a detachable part of the plunger whereby it may be 10 removed for replacement.

The lower bracket 19 is formed to provide a horizontal shelf 24 axially underlying the plunger 21, and said shelf is provided with 15 a perforation 25 into and through which the element 22 is arranged to be reciprocated from a normally withdrawn position above it. The perforation 25 is circular and is of no less diameter than the inside diameter of a pre-formed ferrule ring 15. Preferably, and as 20 shown, the perforation 25 is counterbored from above to provide an annular seat 26 for the centered reception of a ferrule 15. The maximum width of the plunger fork 23 is 25 such that said fork may pass downwardly into and through a ferrule 15 engaged in the seat 26.

It will now be noted that if a fibre bunch 12 be disposed laterally across a ferrule 15 engaged in the seat 26, the projection of the plunger fork 23 transversely against the bunch will force the engaged bunch portion axially into and through the ferrule to provide the handle fold 13 and operatively engage the ferrule about the doubled bunch 30 to provide the brush; Figures 3 and 4 disclose the plunger fork in its final brush forming position. With the present apparatus, I prefer to primarily mount a bristle bunch 12 35 in the raised fork, inserting it from below in the raised fork, inserting it from below through the space provided below the fork, as is shown in Figures 1 and 2. Upon a 40 downward movement of the plunger, the bunch is first engaged laterally across the mounted ferrule and is thereafter folded and 45 forced through the ferrule as described. It is noted that relative adjustment of the brackets 18 and 19 is arranged to control both the loading clearance of the fork and the 50 length of the brush handle.

Reciprocation of the plunger 21 may be effected by any suitable means, a pedally operated lever mechanism being provided in the present instance whereby to leave an operator's hands free for performing the necessary operations at and adjacent the plunger fork. As shown, a pedal 27 is provided on a lever 28 pivoted to the standard 16 adjacent the bottom thereof. A lever 29 fulcrumed at the top of the standard 16, pivotally engages the plunger 21 at its top for reciprocating the same, and the extremities of the rearwardly extending portions of the levers 28 and 29 are connected by a link 31 55 whereby a depression of the pedal 27 effects

a downward movement of the plunger 21 to form a brush, as described. A tension spring 32 connects the rear end of the upper lever 29 with a fixed element of the apparatus, as the bracket 19, to resiliently urge a restoration of the plunger to its raised position whereby such disposition of the plunger is arranged to be automatically effected when pressure on the pedal is released. As shown, a stop screw 30 is provided at the upper end 70 of the plunger 21 for engagement with the bracket 18 to limit the downward movement of the plunger.

It is noted that if the fibre bunches 12 are 75 engaged by the plunger fork at their exact centers, no trimming of the tuft of the brush produced will be required after formation thereof. While such is not shown, the use on the shelf 24, of a suitable positioning gauge 80 for the pre-cut fibre bunches is seen as an obvious expedient for centering said bunches in the fork. It is further noted that the bunches 12 are preferably pre-cut to length in any suitable manner from a continuous 85 and relatively untwisted rope of fibre of suitable diameter; sisal fibre appears on the market in a loose rope form, which is the proper thickness for forming a shaving brush by the disclosed method, and since the sisal fibres have the desired brush bristle qualities, 90 their use is preferred.

After a completed brush has been removed from the plunger fork, it is preferably charged with shaving soap 33 by a dipping or other suitable process, and is then wrapped 100 in a sanitary wrapper 34 for delivery to a user. It is noted that the production of wrapped and soap-charged brushes in the manner now described, represents a minimum of manufacturing cost whereby they 105 may profitably be discarded after being used once or twice. In this manner, the ends of convenience, sanitation and inexpensiveness are all served in the production and use of the present brush.

From the foregoing description, taken in connection with the accompanying drawings, the advantages of the construction and method of use will be readily understood by those skilled in the art to which the invention 110 appertains. While I have described the principle of operation, together with the device which I now consider to be a preferred embodiment thereof, it is understood that the device shown is merely illustrative, and that 115 such changes may be made when desired as fall within the scope of the appended claims.

Having thus described my invention, I claim as new and desire to secure by Letters Patent of the United States, the following:

1. In apparatus for forming a brush of a bunch of bristle material and a preformed ferrule member, a support for the ferrule, and plunger means engageable with an intermediate bunch portion for forcing the 120

same transversely against and axially through said ferrule engaging said support for effecting the compressed and fixed engagement of the said bristle portion in said ferrule bore.

- 5 2. In apparatus for forming a brush of a bunch of bristle material and a preformed ferrule member, a support for the ferrule, and a member of the apparatus for engagement with an intermediate bunch portion for forcing the same transversely against and axially through a said ferrule engaging said support for effecting the compressed and fixed engagement of the said bristle portion in said ferrule bore, said member arranged to be thereafter removed from the brush structure.
- 10 3. In apparatus for forming a brush of a bunch of bristle material and a preformed ferrule providing a bristle-receiving bore, a support element providing a perforation no smaller than the said ferrule bore and a seat for the ferrule at an end of said perforation, and plunger means engageable with an intermediate bunch portion for forcing the same transversely against and axially through a said ferrule engaging said seat for the compressed and fixed engagement of the said bristle portion in said ferrule bore.
- 15 4. In apparatus for forming a brush of a bunch of bristle material and a preformed ferrule ring, a fixed plate element providing a perforation no smaller than the bore of the said ring and a coaxial seat for the ring at an end of the said perforation, and plunger means engageable with an intermediate bunch portion for forcing the same transversely against and axially through a said ring in said seat for compressed and fixed engagement in said ring.
- 20 5. In apparatus for forming a brush of a bunch of bristle material and a preformed ferrule ring, a plate element providing a perforation no smaller than the bore of the said ring and a seat for the ring at an end of said perforation in coaxial relation thereto, a fork element arranged to span said bunch and for projection through said perforation to force the engaged bunch portion transversely against and axially through a said ring in said seat for doubling the bunch through said ring, and means for reciprocating said element to and from said projected position thereof, said doubled bunch portion being arranged to be compressedly gripped in said ring following the removal of said fork therefrom.
